PAPER DOLL OR THE LIKE

Queen Holden, Forest Hills, N. Y., assignor to
 Western Printing & Lithographing Company,
 Racine, Wis., a corporation of Wisconsin

Application October 9, 1942, Serial No. 461,430

17 Claims.

(Cl. 46—36)

This invention relates to improvements in paper dolls or the like.

It is the primary object of the invention to provide novel and improved means for establishing in a planiform figure an illusion of movement. In a person or animal this may involve the opening and closing of a bodily orifice such as the eyes or mouth. For purposes of exemplifying the invention I have illustrated a paper doll with means for apparently opening and closing its eyes.

More specifically stated, it is an object of the invention to provide an otherwise planiform figure with the semblance of an opening at which a planiform flap is pivoted to expose one or the other of its faces, the respective faces of the flap being so decorated as to create a different effect on the figure when the flap is in one position from the effect created when the flap is in its other extreme position.

It is a further object of the invention to provide a novel and improved mechanical structure providing for the pivoting of the flap whose movement creates the illusion or effect desired.

A further object of the invention has to do with novel and improved means for constructing the flap to enable both of its faces to be printed in one operation.

Other objects will be apparent to those skilled in the art upon analysis of the following disclosures of the invention.

In the drawing:

Fig. 1 is a view in front elevation of a paper doll comprising a figure embodying this invention.

Fig. 2 is a fragmentary detail view of the head of the doll, showing the appearance of the doll with the pivoted flap adjusted to give the effect of closed eyes.

Fig. 3 is a fragmentary detail view in rear elevation of the head portion of the figure, showing the flap as it appears when the eyes are open as shown in Fig. 1.

Fig. 4 is a fragmentary detail view of the blank from which the flap is formed.

Fig. 5 is a view taken in vertical section on the line 5—5 of Fig. 3.

Fig. 6 is a detail view taken in horizontal section on the line 6—6 of Fig. 3.

Like parts are identified by the same reference characters throughout the several views.

While the invention may be applied to figures of any desired shape, material, or other characteristics, it may be well exemplified by reference to the paper doll shown in the drawing. The difficulties of creating the illusion of opening and closing eyes in a paper doll are obvious and have

long been well known. In the present exemplification the illusion is created only at the eyes. The figure of the doll is indicated at 7 and comprises a single sheet of paper or thin board having the desired outline and decoration and provided in the face area 8 with simulated eye sockets 9 which, in this instance, are apertures through the sheet which provides the figure.

Pivoted in each aperture 9 is a tab 10. (In this 10 particular exemplification a single tab serves both eye openings.) The tab may conveniently be made by taking paper or the like, approximately half of the weight of that used to make the figure 7, decorating its face as shown in Fig. 4, and 15 thereafter folding and gluing it upon itself so that the two decorated faces are outermost. As clearly appears from Fig. 4, the opposing margins of the blank which comprises tab 10 are provided with arcuately segmental projections 11 and 12 which 20 register with each other when the blank is folded and glued. Each of these segmental extensions terminates adjacent the margin of the blank in a generally radial line such as to form notches at 13 between the segmental extension and the blank 25 proper. The extensions 11 are decorated to represent the open eye, while the extensions 12 are decorated to represent the closed eyelid. When the blank is folded to constitute the tab 10, such tab will have on its upper face the reproduction 30 of two eyelids and on its lower face the representation of two open eyes.

The distance between the notches 13 at each side of the registering extensions 11, 12 of the tab, will preferably correspond almost exactly 35 to the width of the apertures 9 representing the eye sockets so that it is necessary to flex the registering extensions 11, 12, of the tab to manipulate them through the eye sockets. Once in place, as shown in Fig. 6, the engagement of the 40 notches 13 against the margins of the blank 7 at the sides of the sockets 9 will permit the tab to be moved pivotally between the positions shown in full and dotted lines in Fig. 5. When the portion of the tab which is behind the figure 45 7 is raised to the dotted line position shown in Fig. 5, the top surface extensions 12 will be exposed at the front of the figure to create the illusion of lowered lids. When the tab 10 is in its full line position illustrated in Fig. 5, the 50 lower surfaces carrying extensions 11 will be exposed at the front of the figure to create the illusion of raised lids or open eyes as shown in Fig. 1. Fig. 6 shows the tab 10 in an intermediate position in order to illustrate how the hinged mounting thereof on the figure 7 is achieved. Fig. 3,

like Fig. 1 and Fig. 5, illustrates the tab in its lower or open eye position.

While the figure in general is entirely planiform, it will of course be understood that the portion of the image which is carried by the tab need not be exactly in the plane of the rest of the figure but at a slight angle thereto, as clearly shown in Fig. 5. In any event, that portion of the image carried by the movable tab co-operates with that portion of the image carried by the plane of the figure and to the extent that it moves through an arc upwardly from the face of the rest of the figure, the tab creates a remarkably realistic illusion.

I claim:

1. A paper doll or the like comprising a mounting member and a tab pivoted upon the mounting member for movement with respect thereto between extreme positions in which opposite faces of the tab are exposed to view, the mounting member and the tab together providing an image wherein the opposite faces of the tab illustrate image portions in different positions.

2. A device of the character described, comprising the combination with a mounting member portraying a figure having a bodily opening and a tab pivoted to the mounting member at the representation of such opening to swing outwardly from the face of said member in moving between extreme positions in which opposite faces of the tab are exposed in proximity to said member, the opposite tab faces being decorated to show in different positions the bodily feature normally appearing at said opening, whereby such feature appears to change its position as the tab is swung from one such position to the other upon its pivotal connection with the member.

3. In a device of the character described, the combination with a mounting member portraying a figure having an eye socket portion, of a tab pivotally mounted on said member at said eye socket portion and provided with means behind said member for the manipulation of said tab upon its pivotal connection with said member, said tab including a forwardly exposed portion movable outwardly of said member between extreme positions in which said last mentioned portions expose opposite faces in immediate proximity to said member, the said opposite faces of the last mentioned portions being respectively decorated to represent open and closed eyes complementary to the decoration of the mounting member adjacent said sockets, whereby to create an illusion of the opening and closing of the eyes of the figure as said tab is manipulated between its aforesaid positions.

4. The combination with a member having an opening, of a tab extending through the opening and having a portion exposed outwardly of said member, said tab being pivoted in said member for oscillatory movement in said member, contiguous portions of said member and the opposing faces of the outwardly exposed portion of the tab being decorated to represent different positions of relatively movable parts of the same object.

5. In combination with a paper doll provided with eye openings, tab means comprising portions pivoted in the respective eye openings, the upper surfaces of said tab portions being decorated as eyelids and the lower surfaces of said tab portions being decorated as open eyes.

6. The device of claim 5 in which the tab means

pivoted in the respective openings are interconnected for unitary pivotal movement.

7. In combination with a paper doll having eye openings, a tab member having a manipulated portion behind the paper doll and having extension portions projecting through said openings and notched for pivotal connection with the paper doll at the sides of the respective openings, said tab extension portions having their respective upper and lower surfaces decorated to constitute closed and open eye members of said doll.

8. In a device of the character described, the combination with a sheet member having an opening, of a tab member extending through the opening and having behind the sheet member an operating portion, said tab member being laterally notched and engaged with the sheet member for positioning it pivotally in the opening of the sheet member, the respective upper and lower faces of the portion of the tab member extending through the opening being decorated to represent different positions of the same part and the sheet member being decorated to represent an object wherein said part is movable.

9. In combination with a paper doll having a facial opening, a tab member having a first portion behind said doll and an extension portion projecting through said opening and exposed at the front of said doll, said extension portion and the first portion of said tab member having a restricted connection providing opposing notches interlocked with the doll at said opening whereby to provide a pivotal connection between the tab member and the doll, the extension portion of the tab member having opposing faces differently decorated to represent different positions of a facial part movable at said opening and complementary to contiguous portions of the doll face adjacent said opening.

10. In a device of the character described, the combination with an apertured member, of a tab comprising a blank having corresponding projections from its opposite margins and differently decorated at said projections to represent different positions of the same part, said blank being centrally folded and glued with said extensions superimposed and the superimposed extensions being disposed at one side of the apertured member with the remaining tab portions at the other side thereof, said member and tab having at said extensions interlocking means for pivotally projecting the tab respecting said member.

11. In a paper doll, the combination with a doll member having eye apertures, of a tab comprising a blank with a pair of eye extensions correspondingly located to project from each of two opposing margins and differently decorated to represent different eye positions, said blank being centrally folded and adhesively secured with the extensions of the respective pairs registered, each set of registered extensions providing notches at their points of connection with the tab and said notches being interlocked with the doll member in the apertures thereof whereby the decorated faces of said extensions project at the front of the doll member to be alternatively exposed according to the pivotal position of the tab, the tab being disposed behind the doll member for the manipulation of said extensions.

12. In a device of the character described, a sub-combination which comprises a tab constituting a blank centrally folded upon itself and having projections from its opposite margins registered in face contact when folded, said blank providing a continuous face surface across the

fold line differently decorated at the respective extensions, whereby the folded blank has upper and lower extension faces differently decorated.

13. The device defined in claim 12 wherein said extensions and contiguous marginal portions of the blank form opposing notches for the pivotal mounting of the blank.

14. A method of providing the illusion of opening and closing eyes for a paper doll, such method comprising picturing an open eye and a closed eye on opposite faces of the same tab member and pivotally moving the tab member with respect to the face of the doll to swing forwardly of such face about a transverse axis of pivotal movement.

15. A method of creating the illusion of movement of a part of a figure, such method comprising the picturing of said figure part in one position on one face of a tab and in another position on the opposite face of the tab, mounting the

tab pivotally for bodily swinging movement with respect to the figure of which said part is pictured on the tab, and swinging the tab respecting the figure.

5 16. The method making a tab for creating an illusion of movement of a part of a figure, such method comprising the concurrent impression at different points on the same tab blank of pictures of such part in different positions, and folding 10 and fastening the blank upon itself with said parts in registry, whereby the representations of said part are on opposite sides of the folded blank.

17. The method set forth in claim 16 followed by the further mounting of the folded blank in 15 an apertured figure for pivotal movement in the aperture between such positions as alternatively to display the part in its different positions.

QUEEN HOLDEN.
